United States Patent Office

Des. 174,981
Patented June 21, 1955

174,981

LAMP BASE OR SIMILAR ARTICLE

Eve Cohen, West Orange, N. J.

Application April 5, 1955, Serial No. 35,364

Term of patent 7 years

(Cl. D48—20)

To all whom it may concern:

Be it known that I, Eve Cohen, a citizen of the United States, residing in the town of West Orange, county of Essex, and State of New Jersey, have invented a new, original, and ornamental Design for a Lamp Base or Similar Article, of which the following is a specification, reference being had to the accompanying drawings, forming a part hereof:

The figure is a front elevational view of a lamp base showing my new design. The design is substantially circular throughout its entire height. The dominant features of my design are shown in solid lines.

I claim:

The ornamental design for a lamp base or similar article, as shown and described.
